UNITED STATES PATENT OFFICE.

LEWIS W. SAYRE, OF BYESVILLE, OHIO.

RAIL-JOINT.

No. 845,482.

Specification of Letters Patent.

Patented Feb. 26, 1907.

Application filed July 18, 1906. Serial No. 326,696.

To all whom it may concern:

Be it known that I, LEWIS W. SAYRE, a citizen of the United States of America, residing at Byesville, in the county of Guernsey and State of Ohio, have invented certain new and useful Improvements in Rail-Joints, of which the following is a specification, reference being had therein to the accompanying drawing.

10 This invention relates to rail-joints; and its primary object is to provide improved means for connecting the meeting ends of railway-rail sections in such a manner as to provide a practically continuous tread-surface for the 15 rails.

15 A further object of the invention is to provide the meeting ends of railway-rails with interlocking projections and recesses whereby the rails may be securely connected without 20 the use of bolts and nuts and without weakening the web portions of the rails by the formation therein of the usual bolt-holes.

25 The construction of the improvement will be fully described hereinafter in connection with the accompanying drawing, which forms part of this specification, and its novel features will be defined in the appended claims.

30 In the drawings, Figure 1 is a perspective view of the meeting ends of two rails constructed in accordance with my invention. Fig. 2 is a view in perspective of the meeting ends of two rails embodying the invention, the same being separated. Fig. 3 is a side elevation of the rails, and Fig. 4 is a perspective view of the supporting-plate upon which 35 the ends of the rail rest.

35 The reference-numeral 1 designates railway-ties recessed on their upper surfaces to receive a metallic base-plate 2. This plate 40 extends between two adjacent ties, as shown, to support the meeting ends of two rails 3 and 4 and is provided along each edge with a longitudinal flange 5 to embrace the base of the rails.

45 The tread 6 of the rail-section 3 is formed with a tapering projecting tongue 7, adapted to fit within a corresponding recess 8, formed in the end of the tread portion 9 of the rail 4. The web of the rail 3 is also provided with a

tapered tongue 10, fitting a corresponding recess 11 in the web of the rail 4. From the base of the rail 3 projects a tapered tongue 12, adapted to fit a corresponding recess 13 in the base of the rail 4. The rails and the base-plate 2 are secured to the ties by spikes 14, 55 said plate being formed with slots 15 to receive the spikes.

The interlocking of the several tapered tongues projecting from one rail with the corresponding recesses formed in the other rail 60 prevents lateral disengagement of the rails, and the projection of the tongue 7 into the recess 8 of the adjoining rail affords a practically continuous tread-surface. The tongues and recesses provide a secure connecting 65 means for the ends of the rails without the use of bolts and nuts, thus avoiding the weakening of the webs of the rails by the formation therein of bolt-holes.

What I claim, and desire to secure by Letters Patent, is—

1. The combination of two railway-rails having their tread portions connected by a tapered tongue formed on one rail, and a tapering recess formed in the other rail to receive said tongue, and their web portions connected by a tapered tongue projecting from one rail and fitting a corresponding recess in the web of the other rail.

2. The combination of two railway-rails having their tread portions connected by a tapered tongue formed on one rail, fitting a corresponding recess in the tread of the other rail, their web portions connected by a tapered tongue projecting from one rail and fitting a corresponding recess in the web of the other rail, and their base portions connected by a tapered projection fitting a corresponding recess in the base of the other rail, and a base-plate adapted to be spiked to the ties and formed with opposite longitudinal flanges to engage the bases of the rails.

In testimony whereof I affix my signature in the presence of two witnesses.

LEWIS W. SAYRE.
